[57] **CLAIM**

The ornamental design for an occasional chair, as shown and described.

DESCRIPTION

FIG. 1 is a perspective view of an occasional chair showing my new design, having side panels with solid inlay;
FIG. 2 is a left side elevation thereof, the right side elevation being a mirror image;
FIG. 3 is a front elevational view thereof;
FIG. 4 is a rear elevational view thereof, showing the back panel with solid inlay; and,
FIG. 5 is a top plan view thereof.
